(57) **CLAIM**

I claim the ornamental design for a remote control car, as shown and described.

DESCRIPTION

FIG. 1 is a right side elevation view of a remote control car, showing my new design;

FIG. 2 is a left side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a front, right side and top perspective view thereof;

FIG. 8 is a rear, left side and top perspective view thereof;

FIG. 9 is a bottom, left side and front perspective view thereof; and,

FIG. 10 is a bottom, right side and rear perspective view thereof.
